UNITED STATES PATENT OFFICE.

JOHN A. PRINDLE, OF CLEVELAND, OHIO.

DESIGN FOR A PAPER-WEIGHT.

SPECIFICATION forming part of Design No. 14,146, dated July 31, 1883.

Application filed April 17, 1883. Term of patent 14 years.

To all whom it may concern:

Be it known that I, JOHN A. PRINDLE, a citizen of the United States, residing at Cleveland, Cuyahoga county, State of Ohio, have 5 invented and produced a new and original Design for Paper-Weights, of which the following is a specification, reference being had to the accompanying drawing, forming a part thereof.

10 The figure is a front elevation view of my newly-designed paper-weight.

The paper-weight consists of the American eagle, with outstretched wings, resting on a base whose general shape is that of a truncated cone, but that may have curved, irregular, or fanciful outlines, preferably of the ogee 15 pattern shown in the drawing.

I am aware that a paper-weight has been

made consisting of a bell having an eagle mounted thereon, and hence I would have it 20 understood that I make no claim to such design.

What I claim is—

The design for a paper-weight shown and described, the same consisting of an American 25 eagle, with outstretched wings, resting upon a base whose general shape is that of a truncated cone, but with a double curved outline, preferably of the ogee pattern.

In testimony whereof I have signed this 30 specification in the presence of two subscribing witnesses.

JOHN A. PRINDLE.
